United States Patent Office.

HAMMATT BILLINGS, OF BOSTON, MASSACHUSETTS.

Design No. 2,793, dated October 1, 1867.

DESIGN FOR A STATUETTE.

The Schedule referred to in these Letters Patent and making part of the same.

Be it known that I, HAMMATT BILLINGS, of the city of Boston, county of Suffolk, and State of Massachusetts, have invented a new and original Design for a Statuette, of which the following is a full, clear, and exact description, reference being had to the accompanying drawing, which gives a perspective view of the said statuette, and to the letters of reference marked thereon.

This statuette is designed in the form of the national monument to the Forefathers, to be erected at Plymouth, Massachusetts, and consists of an octagonal pedestal, A, on which stands a statue of Faith, B. From the four smaller faces of the pedestal project buttresses C, on which are seated figures emblematic of Morality, Education, Law, and Liberty; three of which figures, viz, Morality, D, Law, E, and Liberty, F, are represented in the drawing. Below these figures are panels containing alto-reliefs *a*. On the four large faces of the main pedestal are panels containing inscriptions *e*, and below are smaller panels.

What I claim as my invention, and desire to secure by Letters Patent, is—
The design for a statuette substantially as herein shown and described.
